UNITED STATES PATENT OFFICE.

MELVIN H. BROWNING, OF PERRY, ILLINOIS.

SEED-SOWING MACHINE.

No. 842,073.

Specification of Letters Patent.

Patented Jan. 22, 1907.

Application filed September 15, 1906. Serial No. 334,779.

To all whom it may concern:

Be it known that I, MELVIN H. BROWNING, a citizen of the United States, and a resident of Perry, in the county of Pike and State of Illinois, have invented an Improved Broadcast Seeder, of which the following is a specification.

My invention is an improvement on that class of broadcast seed-sowing machines which are particularly adapted for sowing clover and other seeds among standing corn or on ground in which corn or other crop has been planted in rows.

The features of novelty are hereinafter described and specifically pointed out.

In the accompanying drawings, Figure 1 is a rear elevation of my improved machine. Fig. 2 is a vertical transverse section on the line *a* of Fig. 3. Fig. 3 is a plan view of the machine. Fig. 4 is a side view of the seed-hopper, together with a supporting-bracket and a portion of the frame of the machine, the frame being shown in section. Fig. 5 is a detail view hereinafter referred to. Fig. 6 is a side view of the seed-distributer proper.

Seed-hoppers 12 are mounted upon a frame composed of telescoping tubes 1 1 and 4 4, the larger tubes 1 1 constituting what may be termed the "main" frame or "body" of the frame, taken as a whole, and the smaller tubes 4 4 are adapted to slide therein. The parts 4 4 thus constitute a supplemental frame which is adjustable with relation to the main frame. The tubes 1 1 composing the main frame are spaced apart and rigidly connected by tie and brace bars 2, and from the rear ends of the latter depend, as shown in Fig. 2, bars 3, which are bent at each end, the lower end forming an axle for running or bearing wheels 3^a. There are two such wheels, as indicated in Figs. 1, 3, the same being spaced apart, so as to run between rows of corn or other plants. Braces 3^b (see Fig. 2) extend from the supporting-bars 3 to the front portions of the frame-bars 2. Thus the said bars and the frame are supported in horizontal position. A tongue or pole 1^a is attached to the middle portion of the main frame. Two of the hoppers are supported upon the main frame, and one is supported on each of the supplemental frames 4 4. There are two supports for each hopper, the same being in the nature of angular brackets 5, (see Fig. 4,) which are clipped to the main tubes 1 or smaller tubes 4.

A seed-discharge funnel 12^a (see Fig. 5) de-

pends from the bottom of each hopper. Supplemental hangers 6 also depend from the bottom of each hopper 12, and to and between the lower ends of these is pivoted a 60 stirrup 7, which supports a seed-tube 8, to whose lower end the seed-distributer 11 is attached. A bevel gear or pinion is attached to the upper end of the seed-tube 8 and secured by clamp-screws, whereby the tube is 65 supported and attached in a manner which permits rotation. The pivotal arrangement of the stirrup 7 also permits the seed-tube with its distributer 11 to swing forward and back, so that if the distributer strikes an obstruction it may pass over the same without 70 injury. Rotation is imparted to the seed-tube 8 from a bevel-pinion on a horizontal shaft 9, which is journaled in the bracket 6. Rotation is imparted to the shaft 9 from a 75 stub driving-shaft, which is supported upon a bracket fixed to the rear portion of the main frame 1. The stub-shaft is driven from the axle of the adjacent running-wheel 3^a by means of sprocket-gearing, as shown in 80 Fig. 2. It will be noted that the point of the seed-funnel 12^a approximates closely the upper end of the seed-tube 8, and the end of the latter is in line with the shaft 9, so that seed will continue to enter the tube 8 even 85 while it may swing backward by reason of contact with an obstruction.

A force-feed is provided by means of a rotatable stirrer or agitator arranged in the funnels of the respective hoppers, and this 90 device is driven by a shaft 10, having its bearings in the frame connections 2 and brackets 5^a, which are pendent from the hoppers 12. (See Fig. 4.) The shaft 10 is driven from the stub-shaft by a sprocket-gearing arranged as shown in Fig. 2. The distributer or seed-scattering device 11 is formed of a cast-metal hub, having four radial wings inclined slightly downward and two conical plates placed one over the other and spaced 95 apart, as shown in Fig. 6. There is a space between the inner ends of the wings into which the seed is delivered from the tube 8. It will be seen that the conical top plate serves as a cover, preventing the wings catching on 100 weeds or other obstructions and also preventing the seed being thrown off except at the periphery of the distributer. The tube 8, with the distributer, being revolved rapidly, the seed is delivered laterally at a slight 105 downward inclination and is distributed evenly.

The machine will ordinarily be made above twelve feet in length; but the frame may be telescoped by uncoupling the feed-shafts 10 (see Fig. 3) and pushing the tubes 4 into the main tubes 1, thus placing the outer hoppers close to the wheels, so that the machine is reduced to about eight feet in length. In practice the gears on the stub-shafts may be made of different diameters to drive the force-feed with greater or less rapidity, and thus sow a greater or less quantity of seed in a given time. In other words, by adjusting the outer wheel on the stub-shafts the feed-shaft 10 may be driven at different speeds and the amount of grain so regulated.

What I claim is—

1. The improved broadcast sower, comprising a frame made of telescopic parts, seed-hoppers mounted and supported upon the main frame and telescopic portions, running-wheels upon which the main frame is supported, seed-tubes pivoted beneath the hoppers and adapted to swing forward and back, seed-distributors attached to the lower ends of said seed-tubes, and gearing operatively connecting the running-wheels with the seed-tubes, whereby the seed-tubes and their attached distributors are rotated as the machine advances, as described.
2. In a broadcast seed-sower of the type indicated, the combination, with the frame and wheel-supports, of hoppers secured upon the frame, seed-tubes pivoted beneath the hoppers and having distributors at their lower ends, funnels pendent from the hoppers and aligned with the seed-tubes for discharging thereinto, and gearing which operatively connects the seed-tubes with the running-wheels, as shown and described.
3. In a broadcast seed-sower of the type indicated, the main frame comprising parallel

tubes 1, and wheel-supports therefor, connecting members whereby the said tubes are held rigidly spaced apart, supplemental frames comprising smaller tubes adapted to slide in those of the main frame and supported thereby, seed-hoppers mounted upon the supplemental frame and also upon the main frame, seed-distributing devices connected with each of the hoppers, rotary shafts for driving the seed-distributors, and means which operatively connect said shafts with the running-wheels whereby the shafts are driven as the machine advances, as shown and described.

4. In a broadcast seed-sower of the type indicated, the combination, with the supporting-frame and hoppers arranged thereon and provided with pendent seed-discharge tubes, of seed-tubes 8 and stirrups in which they are held rotatably, brackets pendent from the hoppers, the aforesaid stirrups being pivotally connected therewith, a driving-shaft aligned with the pivot of the stirrups, and gearing connecting the shaft with the seed-tubes, substantially as described.

5. The combination, with the frame, and hoppers having a pendent seed-discharge tube, of seed-tubes 8, and means for rotating the same, said tubes having at their lower ends a seed-distributer comprising two plates arranged one over the other and spaced apart, radial wings arranged between the plates, a space being left between their inner ends into which the seed is received preliminary to its lateral discharge, as shown and described.

MELVIN H. BROWNING.
